(57) **CLAIM**

The ornamental design for a padlock, as shown and described.

DESCRIPTION

FIG. 1 is a perspective view as seen from the top, front, and left side of a first embodiment of a padlock showing my new design, wherein the first embodiment of the padlock is shown in a first, locked position;

FIG. 2 is a front elevational view thereof, the rear elevational view thereof being a mirror image of the front elevational view;

FIG. 3 is a bottom plan view thereof;

FIG. 4 is a top plan view thereof;

FIG. 5 is a left side elevational view thereof; and

FIG. 6 is a right side elevational view thereof.

FIG. 7 is a perspective view as seen from the top, front, and left side of a second embodiment of a padlock showing my new design, wherein the second embodiment of the padlock is shown in a second, locked position;

FIG. 8 is a front elevational view thereof, the rear elevational view thereof being a mirror image of the front elevational view;

FIG. 9 is a bottom plan view thereof;

FIG. 10 is a top plan view thereof;

FIG. 11 is a left side elevational view thereof; and,

FIG. 12 is a right side elevational view thereof.

The broken lines in FIGS. 1 and 2 showing a notch in the lock shackle is used for illustrative purposes only and forms no part of the claimed design. The broken lines in FIGS. 3 and 9 showing a standard key hole are used for illustrative purposes only and forms no part of the claimed design.
